Patented Oct. 9, 1917.

UNITED STATES PATENT OFFICE.

ALFRED OWEN WILLIAMS, OF DETROIT, MICHIGAN.

FUEL-INJECTION VALVE.

1,242,296.

Specification of Letters Patent.

Patented Oct. 9, 1917.

Application filed August 22, 1916. Serial No. 116,369.

To all whom it may concern:

Be it known that I, ALFRED OWEN WILLIAMS, a citizen of the United States, residing at Detroit, county of Wayne, State of Michigan, have invented a certain new and useful Improvement in Fuel-Injection Valves, and declare the following to be a full, clear, and exact description of the same, such as will enable others skilled in the art to which it pertains to make and use the same, reference being had to the accompanying drawings, which form a part of this specification.

This invention relates to apparatus for injecting liquid fuel into the cylinder or the intake manifold of an internal combustion engine, and has for its object an improved valve construction by which the vaporization of the fuel and its admission into the combustion space in desired quantities is effected through centrifugal force:

Figure 1, is a vertical sectional elevation of my improved valve construction and of the adjacent portion of an engine cylinder.

Fig. 2, is a horizontal sectional view taken along the line $x-x$ of Fig. 1.

Fig. 3, is a horizontal sectional view along the line $y-y$ of Fig. 1.

The device of my invention is designed particularly for use with high compression engines which burn such non-volatile fuels as kerosene or crude oil, which have not hitherto been available for use in the form of comparatively light high speed engines because of the impossibility of feeding oil positively enough in the small quantity required for each working stroke of the engine, at the relatively high speed at which it is customary to run this type of engine.

A represents the engine cylinder, whose walls may, if desired, be provided with water cooling spaces B. In one end is screwed the cap or base C. This cap is axially bored, as is the casing D, which is mounted thereabove, to permit the rotatable engagement therethrough of the hollow spindle E, which is mounted in the bronze bearings I above and below the armature F to rotate therewith, the entire armature being inclosed within the casing D. The rotation of the armature is effected by the passage of a current through the motor from the transmission wires H controlled by knife switch J. The spring-actuated brushes K serve to keep the desired degree of contact with the armature.

Within the cylinder, and axially in line with the bore through the cap C, is the valve cover L, which is screwed into the outwardly flanged end M of the hollow spindle E, 60 which projects downwardly into the upper end of the cylinder A. There is thus enclosed between the parts L and M a chamber or space O, in which is located the mushroomed lower end Q of the valve stem R, 65 and which, when the engine is running, is full of oil. The peripheral edge of this valve head Q is slightly upturned so as to form an annular lip P, which, when in uppermost position, engages tightly between 70 the opposing annular valve surfaces N of the enlargement M of the hollow spindle. At peripheral intervals in the enlargement M along the line $y-y$, are located a plurality of radial holes or passages Z, whose inner ends connect with this annular space M' which is controlled by the annular lip P. The valve head is supported on an upwardly extending stem R, which spacedly engages through the hollow central portion of the 80 spindle E and through the stuffing box Y at the top. Between the head U at the upper end of the stem R and this stuffing box Y is interposed a spring V, which serves to keep the stem R in normally raised position, 85 thus keeping the lip P on the valve head Q in position of closure with respect to the annular space M' in the enlargement M of the spindle.

When it is desired to start the engine, the 90 knife switch J is first closed, and the rotation of the motor F begun, oil having been admitted into the hollow spindle E through the supply pipe S. The engine is cranked, manually or otherwise, to start its operation 95 and the link X whose lower end (not shown) is connected therewith in the usual manner, is thereby pushed upward, thus forcing downwardly the end T of the pivoted lever W at the moment of maximum 100 compression; this in turn forces the valve stem R axially downward, unseating the valve head Q from its seat, and allowing the oil which has made its way downward through the hollow spindle E through the 105 holes G in the valve head Q to proceed through the annular space M' to the several radial holes Z. The high speed of rotation of the entire spindle E and its head M, under the actuation of the armature F effects 110 the centrifugal projection of the oil through these holes into the engine cylinder A.

These holes Z are so small, however, that combined with the very slight unseating of the valve head Q at each working stroke of the engine, only the relatively small amount 5 of fuel desired for each explosion is thus ejected, in very small and minutely broken up particles. A throttling action is thus effected by the valve Q, since the quantity of fuel furnished may be regulated either by 10 variations in the length of time the valve is opened and closed respectively, or by variations in the degree to which it is opened, with a constant time period.

What I claim is:

15. 1. A fuel injection valve, comprising an oil inlet, a rotatable hollow spindle adapted to conduct the oil to the interior of an engine cylinder, a longitudinally movable valve and stem, means for actuating said 20 valve and stem, and means for imparting rotative movement to said rotatable hollow spindle.
2. In a fuel injection valve, the combination of a rotatable hollow spindle, a longitudinally movable valve stem adapted to cooperate therewith in regulating the admission of oil into an engine cylinder, and means for causing the rotation of said hollow spindle to effect the centrifugal feeding of the oil. 25
3. In a fuel injection valve, in combination with a rotatable hollow spindle, a valve mounted on one end thereof, an apertured seat for said valve, a spring adapted to 30 yieldingly hold said valve on its seat, and means for actuating said valve lengthwise of its axis to effect its displacement from its seat.
4. A fuel injection valve, having in combination a radially apertured circular valve 40

seat, a valve member adapted to seat thereon, means for feeding a supply of oil toward said valve and its seat, means for actuating said valve from its seat, and means for contemporaneously rotating said valve to effect 45 the centrifugal projection of the oil flowing past the valve when actuated, through the apertures in the valve seat.

5. In a fuel injection valve, in combination with a rotatable hollow spindle, a peripherally apertured cover carried on one end thereof, a valve member within said cover, adapted to control the flow to the peripheral apertures therein, a longitudinally movable stem engaging within said hollow spindle 55 and carrying said valve member on one end, means for actuating said stem lengthwise of its axis, and means for rotatably actuating said hollow spindle and its apertured cover. 60

6. The combination of a longitudinally movable stem, a valve member mounted on the lower end thereof, means for yieldingly holding the stem in raised position, a rotatable hollow spindle through which said stem spacedly engages, an apertured cover carried on the lower end of said hollow spindle, within which said valve member engages, means for actuating said stem lengthwise of its axis, means for rotatably 65 actuating said hollow spindle and its apertured cover, and means for feeding a supply of oil into said hollow spindle. 70

In testimony whereof, I sign this specification in the presence of two witnesses.

ALFRED OWEN WILLIAMS.

Witnesses:

MARY NEAL,
WILLIAM M. SWAN.
